UNITED STATES PATENT OFFICE.

LEWIS L. GILLILAND AND JOS. R. WAGONER, OF DAYTON, OHIO.

SOFA-BEDSTEAD.

Specification of Letters Patent No. 9,726, dated May 17, 1853.

To all whom it may concern:

Be it known that we, LEWIS L. GILLILAND and JOSEPH R. WAGONER, of Dayton, in the county of Montgomery and State of Ohio, 5 have invented certain new and useful Improvements in the Construction of Sofa-Bedsteads, of which the following is a full, clear, and exact description, reference being made to the accompanying drawings, 10 which make part of this specification, and in which—

Figure 1 represents a view in perspective of our invention as adjusted for a sofa. Fig. 2 represents an elevation of the back of the 15 sofa. Fig. 3 represents a view in perspective of our apparatus as adjusted for a bedstead and Fig. 4 a vertical cross section showing the upper half of the sofa partly turned over in the act of forming a bed- 20 stead.

The operation of this sofa-bedstead, including its self adjustment, will be more clearly understood after an examination of its several parts.

25 When shut up and seen in front as in Fig. 1, it has the outward form and appearance of a sofa. The upper half (A) above the joint (a) which forms the back and arms of the sofa, is constructed separate from the 30 frame (B) below, but is attached thereto by hinges (b) so that while the lower half or frame is fixed in its position, the upper half above the joint (a) opens, or turns over, forward upon the hinges (b) to form a 35 bedstead, as exhibited in Fig. 3.

The lower edge of the front-board (c) is 40 hinged to the lower part of the frame as shown in the cross section and by red lines (d d); and its upper edge is held to its place by the sacking (s) of the seat of the sofa, which is attached thereto. This front edge of the sacking (s) it will be seen is attached farther forward than the hinges (b b); consequently when the upper part of 45 the sofa is turned forward upon those hinges, the canvas sacking of the sofa will be partially relaxed. The canvas being thus relaxed the front board (c) will turn forward and downward on its hinges (d); the 50 advantage of which movement will be hereafter specified in connection with the description of the sofa opened and extended as a bed as shown in Fig. 3.

The back of the sofa as shown in Fig. 2, has two shafts or rollers (e e'), one secured to the lower edge of the upper part of

the sofa and the other to the upper edge of the lower part, so that the joint (a) passes between the rollers. Two detents (f f') are attached to the back and fitted to the pinions (g, g₂) at the extremities of the upper shaft, which is thus comparatively fixed but can at will be turned to take up or let out the sofa sacking in order that it may be more or less stretched by the turning over of the seat. To this shaft is attached the sacking of the sofa and of the bed. The other end of the sacking of the bed is fastened to, and partly wound around the lower shaft (e').

Now suppose the upper or seat part turned forward, then downward, whereby the shaft (e) will be carried over to a level with the shaft (e') and the canvas sacking (c) duly stretched for the bed as exhibited in Fig. 3, 70 the same movement also rotates the shaft (e') by unwinding the straps (n) therefrom which also winds up the sacking (c) in the same degree as the straps (n) are unwound. This turning of the roller (e') elevates the 75 head and foot boards (h) and (h) which are fitted with racks (r) into which pinions (r²) on shaft (e') are geared. These boards are fitted with dove-tailed ribs (j j) that slide in vertical grooves (k k) of the frame (B) 80 of the sofa; an extension (l) of the foot board is pivoted to (h) so as to be turned by the hand in either direction; but instead of the pivot (i) it might have been simply fastened at its lower edge to the frame (B) 85 as at (m). The side straps (n) (n) have buckles by which their length may be regulated as seen in Figs. 3 and 4. These straps are passed over and attached to the shaft (e) and run under the shafts (e') just as 90 the sacking runs over it, thus when stretched or tending to turn the shaft (e') in an opposite direction; and hence by lengthening or shortening these straps, the tension of the 95 canvas sacking (C) will be regulated.

100 The turning forward of the front board (c) of the sofa has been described. Had it been fixed, there would now be a hard ridge along the middle of the bed; but by turning forward, and downward, it leaves every part of the stretched sacking or canvas (C) included between the sides, the head and foot boards, without any prop and free to yield.

110 To reconvert the bedstead into a sofa, the bedding is first drawn into that part of the sacking between (e) and (e'); then as the

front portion of the bedstead is raised and turned back on its hinges (7) the straps (n) will be relaxed and the weight of the bedding will turn the shaft (e') in the direction 5 shown by the arrow (2) thus unwinding the sacking (C) and winding up the straps (n) and depressing the head and foot boards to their places by the pinions and racks; and at the same time the bedding will be snugly 10 folded away out of sight within the sofa.

One other peculiarity remains to be noticed, which is that the upper half through its hinges acts as a loaded lever in keeping the canvas (s) of the seat properly 15 stretched, and when converted into a bed, it similarly acts in an opposite direction to stretch the canvas on which the bedding rests.

Having thus described my improved sofa 20 bedstead what I claim therein as new and desire to secure by Letters Patent is—

1. The hinged front-board so arranged that by the act of turning over the seat to convert the apparatus from a sofa into a bed 25 the front board (c) shall turn down to prevent it from forming a hard ridge under the

sacking, which would be uncomfortable to lie on, and when the seat is turned back again to reconvert the bed into a sofa, the front board shall be lifted up again by the 30 act of turning the seat back into the proper position to support the sacking of the seat.

2. Also the arrangement of the head and foot boards so that the act of shutting up the bed will depress them, and opening it 35 out will elevate them again, substantially as herein set forth.

3. The arrangement of the turning seat of the sofa and the sackings of the bed and seat in such manner that by the turning of 40 the seat to form the bed, the sacking of the latter shall be stretched, and by the turning up again of the seat to re-form the sofa, the sacking of the latter shall be stretched substantially as herein set forth.

In testimony whereof we have hereunto 45 subscribed our names.

LEWIS L. GILLILAND.
JOSEPH R. WAGONER.
